UNITED STATES PATENT OFFICE.

ABRAHAM GOLDBERG, OF NEW YORK, N. Y.

DESIGN FOR CANDY.

Application filed July 15, 1921. Serial No. 485,102. Term of patent 14 years.

To all whom it may concern:

Be it known that I, ABRAHAM GOLDBERG, a citizen of the Republic of Austria, and declarant of intention to become a citizen of the United States, residing at New York, in the county and State of New York, have invented a certain new, original, and ornamental Design for Candies, of which the following is a specification, reference being had to accompanying drawing, forming a part thereof.

The figure is a top plan view of a piece of candy showing my new design.

I claim:

The ornamental design for candy as herein shown.

ABRAHAM GOLDBERG.
